UNITED STATES PATENT OFFICE.

JACOB CAIN, OF ALTOONA, PENNSYLVANIA, ASSIGNOR OF ONE-HALF HIS
RIGHT TO FLODOARDO HOWARD, OF WASHINGTON, D. C.

IMPROVEMENT IN COMBINED PAPER CLIPS AND WEIGHTS.

Specification forming part of Letters Patent No. **172,963**, dated February 1, 1876; application filed
December 21, 1875.

To all whom it may concern:

Be it known that I, JACOB CAIN, of Altoona, in the county of Blair and State of Pennsylvania, have invented certain new and useful Improvements in Combined Paper Clip and Weight; and I do hereby declare that the following is a full, clear, and exact description thereof, which will enable others skilled in the art to which it pertains to make and use the same, reference being had to the accompanying drawings.

The object of producing this invention was not only to furnish a substitute for the awkward and undesirable spring paper-clips in common use for holding sheets of writing-paper, but to combine in the same article the separate function of an ordinary paper-weight.

In the accompanying drawings, Figure 1 represents a view in elevation of my combined paper clip and weight; Fig. 2, a similar view, showing the manner of operating the device to grasp a bank of paper; and Fig. 3, a vertical section.

The device in appearance resembles the familiar weights used principally by apothecaries. In this state it could of course readily perform the function of a paper-weight merely; but to give such weight the additional function of a paper-clip, I provide the weight with a separate bottom disk, *a*, from which a central stem, *b*, rises through a sleeve, *c*, or hollow vertical opening in the main portion or holder *d* of the weight. This hollow sleeve is provided with an annular seat, *e*, upon which the lower end of a spiral spring, *f*, is supported. This spiral spring within the hollow sleeve incloses the stem *b*, which stem projects a short distance above the neck *g* of the weight. This part so projecting is provided with a male thread, which engages with a female thread of a hollow knob or cap, *h*, which, when screwed down, depresses the spiral. The tension of the spring acts upon the annular

seat *e*, to exert a force which keeps the main portion in contact with the bottom disk *a*, or the paper interposed between said disk and holder.

The device may be made of any suitable material, but is preferably made of white metal, plated.

The holder on its obverse may present the appearance of a hollow cup, or it may be made solid, except as to its interior hollow sleeve for the spring and stem.

To operate the device pass the index and second finger under the flange of the neck, with back of hand to desk and ball of thumb upon the cap. Approach the fingers and thumb to each other, and the holder is thereby raised from the bottom disk. In the opening made insert the banked sheets of paper with the free hand, and release the grasp upon the parts of the device; when the paper is securely clipped; for releasing it the same operation, except, of course, the paper is removed instead of being inserted. Each sheet of paper, when full of writing, can readily be released and laid aside without disturbing the bank.

I claim—

A combined paper clip and weight, for the purposes described, consisting of the holder *d*, with its flanged neck *g* and central hollow sleeve *c*, provided with seat *e*, in combination with the bottom disk *a*, provided with rising stem *b*, threaded at its termination to receive the screw-cap *h*, which confines the spring, exerting its force to keep the holder and disk in approach.

In testimony that I claim the foregoing I have affixed my signature in presence of two witnesses.

JACOB CAIN.
